GEORGE WORDINGHAM, OF MILWAUKEE, WISCONSIN

COLLAR SUPPORT

Application filed October 3, 1928. Serial No. 310,120.

This invention relates to apparel and more particularly to a brace or support adapted to be disposed within the neck band of a shirt and support a soft collar and prevent it from being crumpled when a number of shirts are tied in a bundle.

One object of the invention is to provide a device of this character formed of cardboard or other flexible material so that a normally flat support may be bowed longitudinally when fitted into place and retained in its proper position by frictional binding engagement with the collar band of the shirt.

Another object of the invention is to so shape the support that when in use its intermediate portion will extend downwardly under the front of a shirt below the collar band and very effectively support the forward portion of a soft collar attached to the shirt and prevent the collar from becoming crumpled when a number of shirts are bundled at a laundry for delivery to a customer.

The invention is illustrated in the accompanying drawings, wherein

Figure 1 is a perspective view looking at the front of a shirt and showing one of the improved collar supports in use;

Fig. 2 is a view looking at the rear of a shirt with one of the collar supports in place,

Fig. 3 is an enlarged view of the collar support as it appears before being used, and

Fig. 4 is a sectional view taken along the line 4—4 of Figure 1.

The shirt, which is indicated in general by the numeral 1, is of a conventional construction and includes a soft collar 2 which is attached to the shirt. The collar may be of any specific style desired, but in the present illustration is formed with wings 3 at its front which extend downwardly in overlying relation to the front of the shirt below the collar band thereof. It has been found that, when shirts having soft collars attached are bundled after being laundered, the collars often become bent or crushed by the pressure ex-

erted when tying the bundle or by the pressure of other bundles when stacked upon a shelf and this is particularly true if the collar is of the type illustrated which includes depending wings at its front.

In order to prevent the collar from becoming crumpled, I propose to employ a support which is fitted into the collar band of the shirt and extends about the front of the collar with its intermediate portion extending downwardly within the shirt a sufficient distance to very effectively support the depending wings of a collar. This support, which is indicated in general by the numeral 4, consists of a sheet of material having sufficient flexibility to permit it to be bowed longitudinally but at the same time sufficiently stiff to prevent it from easily bending and cracking when in use. This sheet which is shown in Fig. 3 and indicated by the numeral 5 is preferably formed of cardboard which is inexpensive and is so cut that the grain of the cardboard extends longitudinally of the sheet, as indicated by the lines 6 in this figure. This sheet is substantially crescent shaped but instead of defining a true crescent the sheet has its end portions cut off, as shown at 7, so that when the device is in use its ends will extend flush with the upper edge of the side portions of a collar instead of projecting upwardly above the collar. In view of the fact that the sheet is substantially crescent shaped, it increases in depth from its ends towards its intermediate portion and when the support is set in place as shown in Fig. 1, the deeper intermediate portion of the support will project downwardly under the front of the shirt below the collar band and very effectively support the front portion and depending wings 3 of the collar. Therefore, the collar will be provided with a firm backing and will be prevented from being crushed or having its depending wings curled outwardly by pressure exerted when a number of shirts are bundled. It will be noted that owing to the fact that the sheet is substantially crescent shaped, the ends 7 will be in close proximity to the side portions of the collar and will be held in place by the frictional binding of the front portion of the support against the front of the shirt.

ing to the depth or width of the intermediate portion of the support, when said support is flexed and positioned within the neckband of a shirt, said intermediate portion thereof will be disposed at an inclination or angle of less than 45° from the plane of the bosom of the shirt with its lower front portion extending beneath the soft wings or tips of the collar and beneath the bosom of the shirt, below the collar band, as best shown in Fig. 4 of the drawings, thereby not only retaining the collar and bosom in shape but also forming a support for the soft tips or wings of the collar and preventing said tips from wrinkling or curling when a number of said shirts are tied into a bundle.

It will further be noted that owing to the flexibility of the support and the angle or inclination thereof with respect to the bosom of the shirt, said support will tend to yield or flatten when downward pressure is exerted thereon, thus permitting several shirts to be stacked one upon the other into a compact bundle while, at the same time, protecting the collar and preventing the tips of the wings from curling.

When the device is in use, a shirt which has been laundered is placed upon a counter and one of the devices removed from a stack and bowed longitudinally by pressing its ends rearward toward each other. The bowed support is fitted into the neckband of the shirt and when it is released its end portions will spring apart. This causes the device to fit snugly about the front portion of the neckband and have frictional engagement therewith so that it will be held in place and prevented from slipping upwardly out of its proper position. The intermediate portion of the support projects upwardly a short distance above the front of the collar and extends downwardly along the front of the shirt, and serves very effectively to support the collar and prevent it from being crumpled or having its depending wings caused to curl outwardly and upwardly when a number of shirts are bundled.

Having thus described the invention, I claim:

A support for shirts having soft attached collars comprising a flat flexible substantially crescent shaped body portion having its lower edge arcuate continuously throughout its length and having a radius shorter than the radius of its upper edge to form a relatively wide intermediate portion between the upper and lower edges of the support at the center thereof, the upper edge of the support at the opposite ends thereof being inclined downwardly and intersecting the adjacent portion of the lower arcuate edge, whereby when the support is flexed and positioned in the neckband of a shirt, the intermediate portion of the support will be disposed at an angle of less than 45° from the plane of the

bosom of the shirt with the lower front portion of the support extending beneath said bosom below the neckband of the shirt and substantially parallel to and beneath the tips of the wings of the soft collar thereby to form a support for said wings and prevent curling of the tips thereof when several shirts are stacked one upon the other into a compact bundle.

In testimony whereof I affix my signature.

GEORGE WORDINGHAM. [L. s.]
